BACK CUSHION FOR AN OPHTHALMIC CHAIR

John T. Armbruster, Niagara Falls, N.Y., assignor to
American Optical Corporation, Southbridge, Mass.

Filed Feb. 26, 1973, Ser. No. 336,092

Term of patent 14 years

Int. Cl. D6—09

U.S. Cl. D6—201

FIG. 1

FIG. 3

FIG. 2

FIG. 1 is a front, bottom and right side perspective view of a back cushion for an ophthalmic chair in reclining position showing my new design;

FIG. 2 is a front and right side perspective view in upright position; and

FIG. 3 is a rear and left side perspective view thereof.

I claim:

The ornamental design of a back cushion for an ophthalmic chair, as shown and described.
